(57) **CLAIM**

The ornamental design for a boat for substrate processing apparatus, as shown and described.

DESCRIPTION

FIG. 1 is a perspective view of a boat for substrate processing apparatus showing our new design;
FIG. 2 is a front elevation view thereof;
FIG. 3 is a rear elevation view thereof;
FIG. 4 is a right side view thereof;
FIG. 5 is a left side view thereof;
FIG. 6 is a top plan view thereof;
FIG. 7 is a bottom plan view thereof;
FIG. 8 is an enlarged rear view thereof taken along line 8-8 in FIG. 3;
FIG. 9 is a cross-sectional view thereof taken along line 9-9 in FIG. 8; and,
FIG. 10 is a cross-sectional view thereof taken along line 10-10 in FIG. 8.

1 Claim, 10 Drawing Sheets
